UNITED STATES PATENT OFFICE.

GUSTAV PUMPTOW, OF SCHKEUDITZ, GERMANY.

SAFETY DEVICE FOR RAILWAYS.

SPECIFICATION forming part of Letters Patent No. 582,227, dated May 11, 1897.

Application filed December 22, 1896. Serial No. 616,655. (No model.)

To all whom it may concern:

Be it known that I, GUSTAV PUMPTOW, a subject of the King of Prussia, German Emperor, residing at Schkeuditz, Kingdom of Prussia, Germany, have made a new and useful Improvement in Safety Devices for Railways, of which the following is a full and exact specification.

This invention relates to safety devices on railways, and is especially intended to call the attention of the engineer of a moving locomotive-engine to the fact that the tracks are blocked or the gates of the level-crossings open.

15 In the accompanying drawings, Figure 1 is a vertical side view of the device. Fig. 2 is a front view. Fig. 3 is a side view of the contact-lever on an enlarged scale. Fig. 4 is a front view of the same.

20 Similar letters of reference indicate corresponding parts.

For the purposes of this invention there are, at a distance of about twenty to thirty meters, poles *a b c* placed, having cross-bars *d*, the ends of which reach to a line above the center of the tracks. The cross-bar *d* of the middle one of these poles is arranged to swing up and down and is connected with the gates of the nearest crossing or the stop-signal by 25 means of wires *e*. Between the tops of all three poles is a wire *f*, which may be lifted or lowered by means of the swinging arm *d* of the center pole *b*. The wire *e* passes around a pulley *e'*, and when this is turned by pulling the wire the pitman *e''*, connected eccentrically to the pulley and to the arm *d*, will move the latter.

In the normal position the wire *f* is pressed down by the cross-bar *d* of the center pole *b*, 35 so that the contact-lever *g* of the engine may

slide along said wire and strike a bell placed near the stand of the engineer.

The contact-lever *g* is shown in Figs. 3 and 4 and is provided with a fork *h*, having a roller *i*, which is pressed against the wire *f* 45 by means of the counterweight *k*. The axle *l* of the fork *h* works also a second smaller lever *m*, to which a chain *n* is fastened, which chain runs between two rollers *o p* and engages a rod *q*, whereby the bell *r* is sounded. 50

The tension of the wire is necessary in order to avoid the contact of the lever during the speed at which the train runs. This device may be placed at or near level-crossings, and may be connected with the gates by wires. 55 It will increase the safety of railway travel, will prevent the running over of persons, cattle, or vehicles, as the engineer receives in time a signal that the gates are not closed.

I claim—

1. In combination, the wire supported at its ends and extending lengthwise of the tracks, means for raising and depressing the intermediate part of said wire and a contact-lever on the car having connection with a signal on the car, substantially as described. 60

2. In combination, the two end posts, the wire stretched between, the intermediate post, the lever *d* pivoted thereon for lowering the middle part of the wire, means for operating the lever and the signal device on the car to contact with the wire, substantially as described. 70

In testimony whereof I have signed my name to this specification in the presence of 75 two subscribing witnesses.

GUSTAV PUMPTOW.
